Des. 211,971
Patented Aug. 13, 1968

211,971

BOATHOOK

George A. Lasko, 1367 Vulcan St.,
El Cajon, Calif. 92021

Filed Mar. 23, 1967, Ser. No. 6,361

Term of patent 14 years

(Cl. D71—1)

FIG. 1

FIG. 2

FIG. 3

FIG. 4

FIGURE 1 is a side elevation view of a boathook showing my new design. The opposite side is the name.

FIGURE 2 is a side elevation view thereof turned away from the position of FIGURE 1.

FIGURE 3 is a top plan view thereof.

FIGURE 4 is a side elevation view thereof turned in quarter circle from the position of FIGURE 2.

I claim:

The ornamental design for a boathook, as shown and described.
